APPARATUS FOR VIBRATING CONCRETE

William P. Day, Cleveland Heights, Ohio, assignor to The International Vibration Company, Cleveland, Ohio, a corporation of Ohio

Application October 21, 1936, Serial No. 106,771

12 Claims. (Cl. 25—1)

This invention relates to a method of vibrating concrete and to an apparatus and tool for practicing the method although the method may be practiced by an apparatus different from that disclosed herein.

Concrete walls and floors usually contain reinforcing rods or a mesh which serves to strengthen the walls; and heretofore it has been difficult to tamp or vibrate the concrete to cause it to settle.

Such vibration or tamping as has been done has usually been accomplished by means of what is called a spud vibrator which consists of a motor with an off-center weight mounted in a casing which is submerged in the concrete and connected with the power means by a flexible shaft. These spud vibrators are difficult to insert or remove and also do not impart sufficient vibration to the concrete to accomplish the result desired. Attempts have also been made to impart vibrations to concrete by means of different types of power-operated vibrators attached to the forms; but such a method has also been found to be ineffective and unsatisfactory. Tampers have also been used to cause the concrete to settle but these too have not been satisfactory for the reason that sufficient vibrations are not imparted to the concrete or to the reinforcing rods or mesh.

The main object of this invention is to provide a method of vibrating concrete and an apparatus which will practice the method and by means of which rapid and violent vibrations are transmitted throughout the concrete and to the reinforcing rods to cause the concrete to settle to a substantial degree whereby to reduce the moisture content of the concrete and to substantially eliminate voids in the concrete which makes it possible and practical to use a stiff or harsh mix which contains a much smaller percentage of moisture.

Another object of the invention is to provide an apparatus and tool for practicing the method herein described which can be readily inserted into or removed from the concrete and which comprises comparatively few parts and which can be produced at minimum cost.

A further object of the invention is to provide a method of vibrating concrete which consists in immersing in the soft concrete a tool having a rigid portion and one or more flexible portions and then rapidly and violently reciprocating the tool in a plane perpendicular to the horizontal surface of the concrete.

Further and more limited objects of the invention will appear as the description proceeds and by reference to the accompanying drawings in

which Fig. 1 is a view partly in section and partly in elevation showing my improved apparatus with the vibrating tool immersed in a concrete wall; Fig. 2 is a view in side elevation at right angles to Fig. 1 and showing the upper part of the vibrating apparatus; Fig. 3 is a top plan view of the vibrating apparatus; Fig. 4 is a horizontal view of the vibrating tool; Fig. 5 is a vertical sectional view taken on the line 5—5 of Fig. 1; Fig. 6 is a vertical sectional view taken on the line 6—6 of Fig. 5; Fig. 7 is a view in elevation of the eccentric link removed from the apparatus; Fig. 8 is a horizontal sectional view taken on the line 8—8 of Fig. 5; Fig. 9 is a detail sectional view showing the manner of securing the shaft of the vibrating tool to the apparatus; Fig. 10 is a vertical sectional view of a modified form of vibrating tool; Fig. 11 is a view in side elevation of the tool shown in Fig. 10; Fig. 12 is a vertical sectional view showing another modified form of tool; and Fig. 13 is a horizontal sectional view taken on the line 13—13 of Fig. 12.

Referring now to the drawings the apparatus consists essentially of a casing 1 which is shaped as shown most clearly in Figs. 1 to 6 inclusive. Formed integral with the casing 1 are a pair of bosses 2 and 3 having aligned openings therein and in which are positioned bearings 4 and 5. Extending through the bosses 2 and 3 is a hollow shaft or pipe 6 the central portion of which is threaded as shown at 7. The ends of the pipe project through aligned openings provided in the opposite ends of the casing, as shown most clearly in Fig. 5, and are provided with threaded portions 8 and 9 and in which are provided slots 10 and 11. One side of the casing is provided with a rectangular opening which is normally closed by a cover plate 12 which is secured in place by means of bolts 13. Journaled in the casing is a shaft 14 which is mounted in suitable bearings 15 and 16. The shaft is provided with an enlarged portion 17 and an eccentric 18 the purpose of which will hereinafter appear. The shaft is held in place by a pair of cover plates 19 and 20 and one end of the shaft projects outwardly therefrom, as shown at 21 in Fig. 7. The end of the shaft 21 is adapted to be connected with suitable power operated means. Fitting over the pipe 6 and threadedly secured thereto is a member 22 which is held with respect to the pipe by means of a pair of nuts 23 and 24. The member 22 is shaped as shown most clearly in Figs. 5 to 7 inclusive, and has a pair of arms 25 and 26 which are spaced apart and through which extends a pin 27 which is held in place by a head

portion 28 and a nut 29. Jounaled on the pin is a bearing 30.

In order to form a driving connection between the shaft 14 and the member 22 and to convert the rotary motion of the shaft 14 into a reciprocatory motion of the member 22, I have provided an eccentric link 31 which has a circular opening 32 therein and which receives therein the bearing 30. The link 31 also has a circular opening 33 therein and in which is positioned a bearing 34 which is held in place by a pair of arcuate plates 35 and 36 which are secured to the link by means of bolts 37. It will be seen that a rotary motion of the shaft 14 and eccentric 18 will impart a reciprocatory motion to the link 31 which pivots upon the pin 27 and imparts a reciprocatory motion to the member 22 which in turn is rigidly connected with the pipe 6. Extending through the pipe 6 is a reach rod or shaft 38 which is made up of a plurality of sections. Threadedly secured on the opposite ends of the pipe 6 are a pair of locking nuts 39 and 40 which may be tightened to rigidly secure the pipe 6 to the shaft 38 at a plurality of spaced points. The slots 10 and 11 in the ends of the pipe facilitate this clamping action. Each section of the shaft 38 may have adjacent the upper end thereof a circumferential groove 41 and the adjacent ends of the pipe 6 are provided with an inwardly extending circumferential enlargement 42 which is adapted to engage in the groove 41 when the locking nuts are tightened, as shown most clearly in Fig. 9. Closing the casing and surrounding the shaft 38 are a pair of circular plates 43 and 44 which are secured in place by bolts 45 and 46. The casing 1 is adapted to be filled with lubricant and in order to prevent leakage of lubricant along the pipe 6 a pair of packing washers 47 and 48 are provided. The projecting end 21 of the shaft 14 is provided with a keyway 49 to facilitate its connection with a suitable source of power. Each section of the reach rod 38 is provided at the end thereof with a recessed threaded portion 50 which is adapted to receive therein a reduced threaded extension 51 on the next adjacent section. Carried by the lower end of the reach rod is the vibrating tool which consists essentially of a shaft 52 to the lower end of which is secured a pointed head member 53. Slidably mounted on the shaft 52 is a collar 54 which may be adjustably secured in place by means of a set screw 55. Secured to the collar 54 are a plurality of flexible steel wires which are indicated by the reference character 56 the lower ends of which are secured to the head member 53. These flexible wires 56 are preferably formed of twisted steel wire and are sufficiently flexible that when the collar 54 is moved downwardly on the shaft from the position shown in Fig. 1, flexible loops will be formed. The position of the collar 54 on the shaft section 52 determines the size of these loops.

In forming the usual concrete wall, the general practice is to set up form boards in which are positioned a plurality of metal reinforcing rods. The concrete is then poured into the form boards and agitated or tamped or vibrated to cause it to settle. In Fig. 1 the tool is shown as immersed in concrete and the reinforcing rods are indicated by the reference character 57. In most cases these reinforcing rods are sufficiently close together to make it impractical to insert between the reinforcing rods a tool of sufficient size to give the necessary vibration. In view of the fact that the wires 56 are flexible, my tool may be inserted between reinforcing rods which are quite

close together. The flexibility of the wires also permits the ready withdrawal of the tool from the concrete. In addition, the flexible wires being in contact with the rods, also tend to transmit the vibration of the tool throughout the concrete to a considerable degree. If the rods are spaced wider apart than shown in Fig. 1, the collar 54 may be adjusted to adjust the size of the flexible loops. The apparatus is of such size and weight that it can be readily handled by one operator and a pair of handles 58 and 59 are secured to the side of the casing which are grasped in the hands of the operator. These handles are secured in place by suitable bolts 60.

According to the preferred manner of practicing the method, the tool is first inserted within the form boards between the reinforcing rods, as shown most clearly in Fig. 1. The end of the shaft 21 is then connected with a suitable source of power such as a gas engine or an electric motor and rotated at a very high speed. The rotary motion of the shaft 14 imparts a reciprocatory motion to the pipe 6 and shaft 38 and hence to the vibrating tool. The speed of rotation of the shaft 14 is preferably such that the reciprocations imparted to the tool are between 3600 and 4000 per minute. The reciprocations imparted to the tool are very short and preferably do not exceed $\frac{1}{4}$ of an inch. It will thus be seen that rapid and violent reciprocations are imparted to the tool and that the vibratory motion of the tool is also imparted to the reinforcing rods for the reason that they are in contact with the tensioned flexible loops of the tool. Sufficient concrete is poured into the forms to cover the tool and about up to the height shown in Fig. 1. If desired, the tool may then be moved to a different position and the same operation performed, or a plurality of tools may be employed. Vibrations are applied for a sufficient period of time to cause the concrete to settle to a substantial degree and to reduce the moisture content of the concrete and to substantially eliminate voids therein. In most cases, vibrations of from 30 to 60 seconds are sufficient to accomplish the result desired. When a second layer of concrete is laid, the tool is withdrawn until the head member is disposed at a point adjacent the surface of the vibrated concrete. An additional layer of concrete is then poured and the vibrations again applied in a similar manner until the complete wall has been laid. As the tool is raised, the lock nuts 39 and 40 may be loosened to permit the reach rod to pass freely through the pipe 6 so that the sections of the reach rod may be detached and removed as required. It will be seen that the vibrations are imparted to the concrete in a vertical plane, that is, a plane perpendicular to the surface of the concrete. This motion simulates a tamping action although much more effective. The fact that the vibrations are applied in a vertical direction facilitates removal of the tool from the concrete. If desired, a layer of concrete of considerable depth may first be poured into the form and the tool inserted thereinto and the vibrations applied in the manner described. The flexible loops on the tool permit it to be inserted into or removed from the concrete with ease even though the reinforcing rods be spaced a slight distance apart. I have found that with the method herein described, I am able to cause the concrete to settle between 20 and 25 percent and to greatly reduce the moisture content and to substantially eliminate voids. The fact that the vibrations are imparted to the reinforcing rods also causes the

concrete to bond with the reinforcing rods and to produce a stronger structure.

In Figs. 10 and 11 there is disclosed a modified form of tool which consists of a shaft 61 which is preferably rectangular in cross section and to the lower end of which is connected a head member 62 which is also rectangular in shape. Slidably mounted on the shaft 61 is a collar 63 which is adjustably secured in position by means of a set screw 64 and rigidly connected with the collar 63 is a rectangular bar 65. Connecting the members 62 and 65 and disposed on opposite sides of the shaft 61 are a plurality of flexible steel wires 66 and 67. It will be seen that by adjusting the position of the collar 63 on the shaft 61, the size of the flexible loops may be increased or decreased. This tool is operated in the same manner as the tool described in connection with Figs. 1 to 8 inclusive and functions in the same manner.

In Figs. 12 and 13, there is disclosed another modified form of tool which is particularly adapted for use in applying vibrations to concrete floors. This form of tool consists of a shaft 68 which is adapted to be attached to the reach rod and to the lower end of which is rigidly secured a head piece 69 which is preferably rectangular in shape. Slidably mounted on the shaft 68 is a collar 70 which has an outwardly projecting circular flange thereon and to which are secured a plurality of flexible steel wires 71 the lower portions of which normally rest upon the rectangular head member 69, as shown in Fig. 11. By adjusting the position of the collar 70 on the shaft 68, these wires may be moved to the desired position. The collar 70 is held in the adjusted position by means of a set screw 72. This tool is particularly adapted for imparting vibrations to concrete floors and is operated in the same manner as the tools already described and is adapted for attachment to the reach rod 38.

It will now be clear that I have provided a method and apparatus for imparting vibrations to concrete which will accomplish the objects of the invention hereinbefore stated. It is of course to be understood that various changes may be made in the details of the apparatus and tools without departing from the spirit of my invention as the embodiments of the invention herein disclosed are to be considered merely as illustrative and not in a limiting sense. The invention is therefore limited only in accordance with the scope of the appended claims.

Having thus described my invention, what I claim is:

1. A vibrating apparatus for imparting rapid and violent vibrations to soft concrete, comprising a shaft, a head member secured to the lower end of said shaft, a collar mounted on said shaft, a plurality of flexible members each of which has one end secured to said collar and the opposite end thereof secured to said head member and power means for imparting rapid and violent reciprocations to said shaft.

2. A vibrating apparatus for imparting rapid and violent vibrations to soft concrete, comprising a shaft, a head member secured to the lower end of said shaft, a collar slidably mounted on said shaft, a plurality of flexible members each of which has one end secured to said collar and the opposite end thereof secured to said head member, power means for imparting rapid and violent reciprocations to said shaft, and means for adjustably securing said collar in place.

3. A vibrating apparatus for imparting rapid

and violent vibrations to soft concrete, comprising a shaft, a vibratory tool secured to the lower end of said shaft and adapted to be immersed in soft concrete, said tool consisting of a head member and a shaft section, a collar slidably mounted on said shaft section and a plurality of flexible members each of which has one end connected with said collar and its opposite end connected with said head member, and power operated means for imparting reciprocatory motion to said tool.

4. A vibrating apparatus for imparting rapid and violent vibrations to concrete, comprising a shaft, a vibratory tool secured to the lower end of said shaft and adapted to be immersed in soft concrete, said tool including a shaft section, a head member and a collar slidably mounted on said shaft section and a plurality of flexible members each of which has one end connected with said collar and its opposite end connected with said head member, power operated means for imparting a reciprocatory motion to said tool, said flexible members being arranged to provide loops of different sizes when said collar is moved to different positions on said tool.

5. A vibrating apparatus for imparting rapid and violent vibrations to soft concrete comprising a shaft, a tool secured to the lower end of said shaft and adapted to be immersed in soft concrete, said tool comprising a rigid member having one or more flexible members connected therewith and means for imparting rapid and violent reciprocations to said tool.

6. A vibrating apparatus for imparting rapid and violent vibrations to soft concrete comprising a shaft, a tool secured to the lower end of said shaft and adapted to be immersed in soft concrete, said tool comprising a rigid member having one or more flexible loops held under compression and secured thereto and means for imparting rapid and violent reciprocations to said tool.

7. A vibrating apparatus for imparting rapid and violent vibrations to soft concrete comprising a shaft, a tool secured to the lower end of said shaft and adapted to be immersed in soft concrete, said tool comprising a rigid member having one or more flexible loops connected therewith, and means for imparting rapid and violent reciprocations to said tool, and means for varying the size of said loops.

8. A vibrating apparatus of the character described comprising a casing, a shaft journaled in said casing and having one end projecting therefrom, a tubular member slidably mounted in said casing and adapted to receive a shaft therethrough, said first mentioned shaft having an eccentric thereon, connections between said tubular member and eccentric whereby a rotary movement of said eccentric will reciprocate said tubular member, means for rigidly securing said tubular member to said second mentioned shaft, and a reciprocatory tool carried by the lower end of said last mentioned shaft.

9. A vibrating apparatus of the character described comprising a casing, a shaft journaled in said casing and having one end projecting therefrom, a tubular member slidably mounted in said casing and adapted to receive a shaft therethrough, said first mentioned shaft having an eccentric thereon, connections between said tubular member and eccentric whereby a rotary movement of said eccentric will reciprocate said tubular member, means for rigidly securing said tubular member to said second mentioned shaft, and a reciprocatory tool carried by the lower end of

said last mentioned shaft and comprising a rigid member having one or more flexible members thereon.

5 10. A vibrating apparatus for imparting rapid and violent vibrations to soft concrete comprising a casing, a shaft journaled in said casing and adapted for rotary movement, a second shaft mounted for reciprocatory movement in said casing, means for converting a rotary movement of said first shaft into a reciprocatory motion of said second shaft, a reach rod rigidly secured to said second shaft and a vibratory tool carried by the lower end of said reach rod.

10 15. 11. A vibrating apparatus for imparting rapid and violent vibrations to soft concrete comprising a casing, a shaft journaled in said casing and adapted for rotary movement, a second shaft mounted for reciprocatory movement in said casing, means for converting a rotary movement of said first shaft into a reciprocatory motion of said second shaft.

20

said second shaft, a reach rod rigidly secured to said second shaft and a vibratory tool carried by the lower end of said reach rod, said vibratory tool comprising a rigid member and one or more flexible members secured thereto.

5 10 15. 12. A vibrating apparatus for imparting rapid and violent vibrations to soft concrete comprising a casing, a shaft journaled in said casing and adapted for rotary movement, a second shaft mounted for reciprocatory movement in said casing, means for converting a rotary movement of said first shaft into a reciprocatory motion of said second shaft, a reach rod rigidly secured to said second shaft, a vibratory tool carried by the lower end of said reach rod and comprising a shaft, a lower member carried by said shaft, an upper member carried by said shaft, a plurality of flexible wires connecting said members, one of said members being slidably mounted on said shaft.

WILLIAM P. DAY. 20
